FIG. IV.

Inventor:

Darius Wilcox
By Knight Bros. attys

UNITED STATES PATENT OFFICE.

DARIUS WILCOX, OF ANSONIA, ASSIGNOR TO WILCOX & HOWE, OF BIRMINGHAM, CONNECTICUT.

FIFTH-WHEEL.

SPECIFICATION forming part of Letters Patent No. 358,316, dated February 22, 1887.

Application filed November 29, 1886. Serial No. 220,159. (No model.)

To all whom it may concern:

Be it known that I, DARIUS WILCOX, a citizen of the United States, and a resident of Ansonia, in the county of New Haven and State of Connecticut, have invented an Improvement in Fifth-Wheels, of which the following is a specification.

My invention is an improvement in the means for connecting the head-block and its plate to the upper member of a fifth-wheel.

As heretofore constructed it has been customary to connect the head-block plate directly to the bolt which secures the parts together thus bringing lateral strain on the bolt, which causes the latter to become loose.

The object of my invention is to provide means for securing the parts together which will overcome the disadvantage referred to.

To this end my improvement consists in surrounding the portion of the bolt (which crosses the meeting faces of the upper member of the fifth-wheel and the head-block plate, and with which the head-block plate heretofore came in contact) with a box or boss, which may either project upward from the upper member of the fifth-wheel, or project downward from the head-block plate into a recess in the upper member of the fifth-wheel, so as to extend across these meeting faces; or in the place of the box or boss I may substitute a thimble, occupying such a position as to extend downwardly into the upper member of the fifth-wheel and upwardly into the head-block plate, the sides of the box or thimble being made either flat or curved, as hereinafter described.

In order that my invention may be fully understood, I will proceed to describe it with reference to the accompanying drawings, in which--

Figure I is a plan view of the upper member of a fifth-wheel and adjacent parts to which my invention is applied. Fig. II is a vertical longitudinal section thereof on the line II II, Fig. I. Fig. III is a transverse vertical section longitudinal of the head-block on the line III III, Figs. I and II. Fig. IV is a vertical section through the head-block, showing a thimble substituted for the box or boss. Fig. V is an enlarged vertical section on the line V V, Fig. I, showing my preferred

construction. Fig. VI is a perspective view of one end of the upper member, showing a round box or boss formed thereon. Fig. VII is a similar view, showing a flat-sided box or boss. Fig. VIII is a perspective view of one end of the head-block plate, showing the round box formed thereon. Fig. IX is a similar view showing the flat-sided box or boss formed thereon. Fig. X is a perspective view of a round thimble. Fig. XI is a similar view of a flat-sided thimble.

1 is the upper member of a fifth-wheel; 2, the head-block; 3, the head-block plate; 4, the reach-bars, and 5 the reach-sockets, the latter being swaged to the head-block plate, as usual.

6 are the bolts, and 7 the nuts thereon, by which the head-block, the head-block plate, and the upper member of the fifth-wheel are secured together. Instead of connecting the ends of the plate 3 directly to the bolts, I construct a box or boss around each bolt. This box or boss may be formed in one piece with the upper member of the fifth-wheel, and extending upwardly and fitting closely, as shown at 8 in Figs. III, V, VI, and VII, into an enlarged bolt-opening in the plate, will remove all lateral strain from the bolt, or it may be formed in one piece with the head-block plate and extend downwardly, as shown at 9 in Figs. III, VIII, and IX, into a recess around the bolt-opening in the upper member; or it may be in the form of a thimble, 10, extending upwardly and downwardly across the meeting faces of the upper member and plate, as shown in Figs. IV, X, and XI, into the said parts.

The boxes or bosses may be either round, as shown in Figs. VI and VIII, or flat-sided, as shown in Figs. VII and IX. The thimble also may be either round, as shown in Fig. X, or flat-sided, as shown in Fig. XI.

I do not limit myself to the precise forms of boxes or thimbles shown, as I may construct them of triangular, hexagonal, octagonal, or other non-circular form, or in elliptical, oval, or other curved form.

The provision of the described box or thimble relieves the bolt of lateral strain, and the latter is not, as protected, liable to become loose.

Having thus described my invention, the fol-

following is what I claim as new therein and desire to secure by Letters Patent:

1. The combination, with the upper member of a fifth-wheel, the head-block, the plate, and the securing-bolt, of the box or thimble surrounding the bolt for taking the lateral strain of the plate off the bolt, substantially as described.
2. The combination, with the head-block,

of a plate having openings for the securing bolts, an upper member of a fifth-wheel, and boxes surrounding the bolts for taking the lateral strain of the plate off the bolts, substantially as described.

DARIUS WILCOX.
